CLAIM

The ornamental design for a position indicator bracket as shown and described.

DESCRIPTION

FIG. 1 is a perspective view of a position indicator bracket, according to the present invention;

FIG. 2 is a front elevational view of the position indicator bracket of FIG. 1;

FIG. 3 is a rear elevational view of the position indicator bracket of FIG. 1;

FIG. 4 is a right side elevational view of the position indicator bracket of FIG. 1;

FIG. 5 is a left side elevational view of the position indicator bracket of FIG. 1;

FIG. 6 is a top plan view of the position indicator bracket of FIG. 1; and,

FIG. 7 is a bottom plan view of the position indicator bracket of FIG. 1.

The broken lines shown are included for the purpose of illustrating portions of the position indicator bracket and form no part of the claimed design.

1 Claim, 4 Drawing Sheets
